MISSOURI.

SIGNALING SYSTEM.

1,091,465.

Specification of Letters Patent. Patented Mar. 24, 1914.

Application filed October 22, 1912. Serial No. 727,186.

To all whom it may concern:

Be it known that we, FREDRICK B. ADAM and LLOYD H. ARENS, both citizens of the United States, residing at St. Louis, Missouri, have invented a certain new and useful Improvement in Signaling Systems, of which the following is a full, clear, and exact description, such as will enable others skilled in the art to which it appertains to make and use the same.

This invention relates to signaling systems of the type that comprise a plurality of electrically-operated signals and means for causing certain of the signals to operate automatically at a certain period, others to operate automatically at a different period, and so forth, the automatic means generally used for governing the signals consisting of a clock and controlling mechanisms combined with the clock in such a manner that the separate electric circuits in which the different groups of signals are arranged are closed automatically at certain periods so as to cause the signals to operate.

One object of our invention is to provide means of novel construction for permitting any signal of a signaling system of the character mentioned to be operated manually or at the will of an operator without affecting or disturbing the automatic signal-controlling means.

Another object is to provide a signaling system controlling device which is so designed that it can be adjusted so as to enable it to coöperate with any of the automatically-controlled signaling circuits of the system.

Another object is to provide a device that combines the functions of a push-button switch which controls an electric circuit that is normally open and also the functions of a switch that normally closes a separate and distinct automatically-controlled electric circuit, the device being so constructed that when it is actuated manually to close the push-button switch circuit the automatically-controlled circuit will be opened simultaneously.

Another object is to provide a device of the character described that comprises a movable conducting member, a plurality of separate and distinct line contacts, each of which is connected to a different automatically-controlled electric circuit, a common line contact, and a separate and distinct con-

tact which is connected to a manually-controlled circuit, said conducting member being constructed in such a manner that it normally engages the common line contact and one of the automatically-controlled circuits, the manual operation of the device causing said conducting member to move out of engagement with the automatically-controlled circuit contact and into engagement with the manually-controlled circuit line contact and thus close or complete the manually-controlled circuit through the common line contact. And still another object is to provide a device of the character just described that is simple and compact and in which the movable conducting member can be adjusted so as to coöperate with any of the separate and distinct automatically-controlled circuit contacts that coöperate with the common line contact.

Other objects and desirable features of our invention will be hereinafter pointed out.

We have herein illustrated our invention embodied in a bell-ringing system that is particularly adapted for use in schools or other public buildings in which a program or course of procedure is announced by bells that operate automatically at certain periods so as to indicate a change in the program. Said system comprises a clock, a plurality of electric circuits, each of which energizes a number of bells located in different rooms of the building and an automatic-controlling means in each of said circuits, governed by the clock, for causing the bells on one circuit or in one group of rooms to ring automatically at a certain period, those on another circuit or in a different group of rooms to ring automatically at a different period, and so forth.

The system comprises a number of manually-operated devices corresponding to the number of bells in the system for enabling any bell in the system to be rung manually or at the will of the person who is in charge of said manually-operated devices without affecting or disturbing the mechanism that causes the bells to ring automatically, said manually-operated devices being grouped together and each device comprising means for enabling it to be connected up to any of the automatically-controlled circuits of the system by simply making a slight adjustment in the device. We do not wish it

to be understood, however, that our invention is limited to a device of the character above described for use in a bell-ringing system for the invention is applicable to 5 various kinds of signaling systems.

Figure 1 of the drawings is a diagrammatic view of a bell-ringing system equipped with devices constructed in accordance with our invention; Fig. 2 is a side elevational view of one of the manually-operated devices that normally closes or completes the particular automatically-controlled circuit in which it is arranged but which opens or breaks said automatically-controlled circuit and simultaneously closes a separate manually-controlled bell-ringing circuit when the device is actuated; Fig. 3 is a side elevational view of said device showing the movable conducting member thereof shifted 10 into position to open the automatically-controlled circuit and to close the manually-controlled bell-ringing circuit; Fig. 4 is a vertical longitudinal sectional view of the device shown in Fig. 2; Fig. 5 is a top plan view of said device; Fig. 6 is a detail vertical sectional view taken on the line 6-6 of Fig. 5; and Fig. 7 is a horizontal sectional view taken on the line 7-7 of Fig. 3, looking in the direction indicated by the 15 arrow.

Referring to the drawings which illustrate the preferred form of our invention, A designates a clock, and B designates a plurality of automatic circuit-controlling members governed by said clock for causing bells arranged in separate and distinct electric circuits 1, 2, 3 and 4 to operate automatically at certain periods, the bells in circuit 1 ringing at certain periods so as to form one 20 program, those in circuit 2 at a different period so as to form another program, and those in circuits 3 and 4 at different times so as to form still other programs, it being, of course, understood that each of said automatically-controlled circuits 1, 2, 3 and 4 energizes different sets or groups of bells located in different rooms of the building in which the system is installed so that the bells in rooms 1, 2 and 3, for example, which 25 are on circuit 1 will ring simultaneously at certain periods, those that are in rooms 3, 4 and 5 which are on circuit 2 will ring simultaneously at different periods, and so forth.

55 While we have herein illustrated a system that comprises four automatically-controlled circuits, it will, of course, be understood that it is immaterial so far as our invention is concerned how many automatically-controlled circuits are comprised in the system. The system also comprises a number of manually-operated devices which make it possible to ring the bells manually or at the will of an operator without affecting or disturbing the automatic mechanism 60 65

that controls the circuits 1, 2, 3 and 4. The manually-operated devices preferably correspond in number to the number of bells in the system so that one manually-operated device will be provided for each bell, but, if desired, the system could be so arranged that one manually-operated device could control several bells. Preferably, said manually-operated devices are mounted on a panel board or other suitable supporting 70 structure in one room of the building so as to enable the person in charge of same to manually ring any bell in the system.

Referring to Figs. 2 to 7 of the drawings, inclusive, which illustrate the details of construction of one of the manually-operated controlling devices, all of which are of the same construction, C designates a member formed of insulating material and provided with spring-contacts w, x, y, z, arranged 80 longitudinally thereof and terminating beyond the end of the member C, each of said contacts being provided with a binding-post 10 so as to enable the automatically-controlled circuits 1, 2, 3 and 4 to be electrically 90 connected to the contacts w, x, y, z, respectively. In addition to the contacts just described the member C is provided with a spring contact v which we will term a common line contact, and also with a spring 95 contact u which we will term a companion contact or a manually-controlled circuit contact, the common line contact v being electrically connected to one leg or branch of an electric circuit 5 that leads to the clock 100 A and in which a bell 6 is arranged, said circuit being energized by a battery 7. When electrical connection is established between the common line contact v and one of the contacts w, x, y, z, one of the automatically-controlled circuits will be closed 105 so far as the manually-operated controlling device is concerned. The spring contact or companion contact u on the member C is electrically connected to a branch line 8 that leads to the battery 7, as shown in Fig. 1, so that when electrical connection is established between the contacts u and v the manually-controlled circuit of which the line 8 forms one branch, will be energized 110 and thus cause the bell 6 to ring. Normally, however, this manually-controlled bell circuit is open or inoperative, and one or another of the contacts w, x, y, z, is electrically 115 connected to the common line contact v so as to complete the automatically-controlled circuit with which the particular device is used.

The means that we prefer to use for normally establishing electrical connection between the common line contact v and one or another of the contacts w, x, y, z, consists of a movable conducting member D carried by a block E of insulating material that is secured to a spring-actuated plunger F 125 130 135

which extends longitudinally through the body portion C of the device. A coiled expansion spring 12 is interposed between the head 13 on the plunger F and the bottom 5 of the socket in the body portion C into which the head or finger-piece 13 projects, as shown in Fig. 4, so as to normally hold the conducting member D in the position shown in Fig. 2 and thus cause a depending 10 lip 14 on the conducting member D to engage one or another of the automatically-controlled circuit line contacts w, x, y, z, and thus complete the circuit through the common line contact v that bears against 15 the conducting member D. When the finger-piece 13 of the device is pushed inwardly, as shown in Fig. 3, the conducting member D engages the contact u of the manually-controlled circuit, thereby completing said 20 circuit through the common line contact v which always remains in engagement with the conducting member D, the depending lip 14 on the member D being so proportioned that it moves out of engagement with 25 its coöperating line contact and thus opens the automatically-controlled circuit just before said member D moves into engagement with the contact u so as to close the manually-controlled circuit 8.

30 In order that the device may be connected up to either of the automatically-controlled circuits 1, 2, 3 and 4, we have constructed the movable conducting member D in such a manner that it can be turned or rotated so as 35 to bring the depending lip 14 thereon into engagement with either of the line contacts w, x, y, z, and have also provided means for locking the member D in adjusted position.

40 In the embodiment of our invention here-
in shown the plunger F that carries the conducting member D is screwed into the finger-piece 13, thus permitting said plunger and conducting member D to be rotated with relation to the body portion C of the device, and an adjustable locking plug 15 is 45 mounted in the conducting member D so as to project into one of a plurality of holes 16 in the body portion C of the device and thus lock the conducting member D in ad-
justed position, as shown in Figs. 4 and 6. Four of the holes 16 are arranged opposite the line contacts w, x, y, z, as shown in Fig. 7, so as to permit the member D to be locked in such a position that the lip 14 thereon 50 will coöperate with the contact of the particular automatically-controlled circuit that has been selected, and one of the holes 16 is arranged opposite the common line contact v to as to lock the conducting member D in a neutral position or in such a position that the lip 14 thereon will not coöperate with either of the line contacts w, x, y, z.

55 All of the manually-operated controlling devices just described are preferably mounted on a panel board or other suitable sup-

porting structure and the line contacts w, x, y, z, of said devices are connected to the automatically-controlled circuits 1, 2, 3 and 4, as shown in Fig. 1. The common line contact v of each device is connected to one side 70 of the particular bell 6 with which said device is used, and the contact u of each device is connected to a common battery circuit 8, as shown in Fig. 1. All of the devices that coöperate with the bells which it is desired to have controlled by the circuit 1 are so adjusted that the depending lips 14 of the movable conducting member D will coöperate with the contacts w. The devices that coöperate with the bells which it is desired to have controlled by the circuit 2 have 75 their conducting members D adjusted in such a position that the lips 14 thereon will coöperate with the line contacts x, the devices that coöperate with the bells which it is desired to have controlled by the circuit 3 being so adjusted that the depending lips on their conducting members D will coöperate with the line contacts y, and the devices that coöperate with the bells which it is desired to have controlled by the circuit 4 being so adjusted that the depending lips on their conducting members D will coöperate with the contacts z. The clock A and automatic controlling members B cause the bells 80 on the different circuits to ring automatically at certain periods and whenever it is desired to ring a particular bell of the system manually this can be accomplished by simply pressing inwardly on the finger-piece 13 of the device that coöperates with or controls that particular bell, the inward movement of said finger-piece causing the conducting member D to move inwardly so as to break or open the automatically-controlled circuit and simultaneously close the manually-controlled bell circuit 8. If it is desired to change a bell from one circuit to another, for example, from the circuit 1 to the circuit 2, the conducting member D of 85 the manually-operated device that controls that particular bell will be turned slightly so that the depending lip 14 thereon will coöperate with the line contact x that is connected with the circuit 2 instead of with the line contact w that is connected with the circuit 1.

90 From the foregoing it will be seen that in a system of the character above-described the devices that permit the bells to be rung manually comprise as an integral part thereof of push-button switches and contacts that are connected to the automatically-controlled circuits of the system, thereby overcoming the necessity of using a controlling 95 or selecting apparatus separate and distinct from the push-button switches that operate the bells manually. In other words, our improved system comprises manually-operated bell-ringing devices, each of which combines 100 105 110 115 120 125 130

the functions of a push-button switch and the functions of a program selector or selecting device which can be adjusted easily so as to enable any bell of the system to be placed in any of the automatically-controlled circuits of the system. Furthermore, the manually-operated bell-ringing devices are so constructed that all of the contacts of each device are kept clean by rubbing against and along one another under pressure when the device is actuated, thereby insuring a reliable conducting device which is not apt to get out of order or become inoperative.

15 Having thus described our invention, what we claim as new and desire to secure by Letters Patent is:

1. A combined switch and circuit-closing device comprising a normally stationary means that closes one of a group of circuits and which is adapted to be actuated at the will of the operator so as to open said circuit and close an independent circuit, said means being so designed that it can be adjusted to coöperate with any desired circuit of said group of circuits without rendering it inoperative with relation to said independent circuit.

2. A combined switch and circuit-closing device provided with a set of contacts, a common line contact, a companion contact, and a normally stationary means that establishes electrical connection between the common line contact and one contact of said set of contacts but which is adapted to be moved so as to open the circuit in which the said contact of said set is arranged and establish electrical connection between the common line contact and the companion contact, said means being so constructed that it can be adjusted so as to normally establish electrical connection between the common line contact and any one contact of said set of contacts.

45 3. A combined switch and circuit-closing device provided with a common line contact, a set of coöperating contacts, a manually-operated movable conducting member which is normally at rest and establishes electrical connection between the common line contact and one contact of said set but which can be arranged so as to coöperate with any desired contact of said set, and a separate contact that is adapted to be engaged by said conducting member so as to coöperate with the common line contact when said member is moved.

4. A combined switch and circuit-closing device provided with a common line contact, a set of coöperating contacts, a manually-operated movable conducting member that normally establishes electrical connection between the common line contact and one contact of said set, said conducting member being normally at rest, and a separate contact

that is adapted to be engaged by said conducting member so as to coöperate with the common line contact when said member is moved, said conducting member being adjustable so that it can be arranged in position to coöperate with any one contact of said set of contacts.

5. A combined switch and circuit-closing device comprising a body portion provided with a set of contacts, a common line contact, a manually-operated movable conducting member that is normally stationary and which always remains in engagement with said common line contact, said conducting member being provided with a portion that engages one contact of said set when said member is in its normal position but which can be adjusted to coöperate with any one contact of said set of contacts, and a separate contact on said body portion arranged in position to be engaged by said conducting member when said member is moved.

6. A combined switch and circuit-closing device comprising a body portion provided with a set of contacts, a common line contact, a manually-operated movable conducting member that is normally stationary and which always remains in engagement with said common line contact, said conducting member being provided with a portion that engages one contact of said set when said member is in its normal position, a separate contact on said body portion arranged in position to be engaged by said conducting member when said member is moved, said conducting member being adjustable so that it can be arranged to coöperate with any one contact of said set of contacts, and means for retaining said member in adjusted position.

7. A combined push-button switch and circuit-closing device comprising a body portion provided with a set of contacts that project beyond one end of same, a normally stationary plunger in said body portion provided at one end with a conducting member that normally engages one contact of said set but which can be adjusted so as to coöperate with any contact of said set, a common line contact on said body portion that always remains in engagement with said conducting member, and a separate contact on said body portion terminating beyond said set of contacts and arranged in the path of movement of said conducting member, said plunger being adapted to be actuated so as to cause the conducting member on same to engage said separate contact.

8. A combined push-button switch and circuit-closing device comprising a body portion provided with a set of contacts that project beyond one end of same, a manually-operated plunger in said body portion provided at one end with a conducting member that normally engages one contact of said

- set, a common line contact on said body portion that always remains in engagement with said conducting member, a separate contact on said body portion terminating 5 beyond said set of contacts and arranged in the path of movement of said conducting member so that said conducting member will engage same when the plunger is actuated, said conducting member being adapted to be 10 adjusted with relation to said body portion so as to enable it to coöperate with any one contact of said set of contacts, and means for locking said member in adjusted position.
- 15 9. A combined push-button switch and circuit-closing device consisting of a body portion of insulating material provided with a set of spring contacts that terminate beyond the inner end of said member, a manually-operated plunger mounted in said body portion and provided at its front end 20 with a finger-piece by which said plunger can be moved rearwardly with relation to

said body, a conducting member on the rear end of said plunger having an extension 25 which normally engages one contact of said set, said conducting member being so constructed that it can be rotated so as to co-operate with any one contact of said set of contacts, means coöoperating with the body 30 portion of the device for holding said conducting member in adjusted position, a common line contact on said body portion that normally engages said conducting member, and a separate spring contact on said body 35 portion that terminates beyond said set of contacts.

In testimony whereof, we hereunto affix our signatures, in the presence of two witnesses, this seventeenth day of October, 1912. 40
